FRANCIS C. OSBORN, OF DETROIT, MICHIGAN.

SOAP-POWDER DISPENSER.

1,226,803.

Specification of Letters Patent. Patented May 22, 1917.

Application filed March 1, 1912. Serial No. 680,842.

To all whom it may concern:

Be it known that I, FRANCIS C. OSBORN, a citizen of the United States, and a resident of Detroit, in the county of Wayne and State 5 of Michigan, have invented a new and useful Soap-Powder Dispenser, of which the following is a specification.

This invention relates to containers for soap-powders, tooth-powders and other materials of like character, which are used in small quantities for toilet and other purposes; and its object is to provide a dispensing device which can be operated by the hand that is to receive the contents; to provide a dispensing device which shall consist in part of the original package in which the powders dispensed are sold; and to provide a dispensing device which shall be strong and simple in construction, which may be 15 easily operated and which may be easily cleaned.

This invention consists in combination with an outer receptacle having a discharge opening in its bottom, of an inner container, 20 preferably the package in which the article to be dispensed is sold; in combination with means for so moving the inner container within the outer receptacle that a portion of the contents will be permitted to escape from 25 the dispensing device.

In the accompanying drawing Figure 1 is a rear elevation of this improved dispenser secured to the faucet of a washstand. Fig. 2 is a section on the line 2-2 of Fig. 1 on 30 a larger scale. Fig. 3 is a section on the line 3-3 of Fig. 1.

Similar reference characters refer to like parts throughout the several views.

Dispensers for soap-powders and liquid 35 soaps have become popular with the owners of hotels and other institutions having public wash-rooms for sanitary reasons, and because of the economy resulting from the saving of soap, which was so often stolen by 40 those making use of the wash-rooms. These dispensers are usually constructed in such a manner as to require both hands, of the person desiring to use the contents, to operate the device. The present invention is 45 embodied in a dispenser which may be operated by one hand, and with very little effort.

A bracket 1 of any desirable construction connects to the body 2 of a faucet at its lower end, but this construction may be 50 varied as desired, and as circumstances require. At the upper end of the bracket is

connected a cylindrical receptacle 3 provided with a top 4, preferably removably secured to the body by means of the well known bayonet-joint 5. The body is formed with a slot 6 through which any desirable connecting devices, such as rivets 7, extend between the plates 8 and 9. The plate 9 within the container is bent so that its lower end 10 extends inwardly. The outer plate 8 has a flat finger-piece 12, so that when a hand is placed underneath the bottom of the receptacle 3, as indicated in Fig. 2, the fingers may extend upward against this finger-piece 12 so that the plates 8 and 9 may be pushed upward while the palm remains in position to receive the powder discharged from the dispenser. At the center of the bottom 13 of the receptacle, are a series of holes 14 and an upwardly extending stud 15, having 75 a pointed knob 16 at its upper end, and a conical lower end 17.

The powders to be dispensed will preferably be sold in a package or container 18, having a cover 19, and whose inner head 20 is preferably conical. The head 20 is formed with a perforation over which is pasted a membrane, preferably a thin piece of paper 21, sufficiently strong to prevent the contents from escaping or breaking through.

When the top 4 is removed, the package 18 may be inserted and pressed down against the point 16, which will pierce the membrane 21, until the parts rest as shown in Fig. 2, with the lower edge of the body 18 on the plate 10 and the tapering portion 17 of the stud 15 acting as a plug for the hole in the head 20. When it is desired to withdraw some of the contents, the hand is placed beneath the dispensing device with fingers engaging the plate 12, which plate is then pushed upward. The part 10 raises the receptacle so that the head 20 is lifted from the tapering portion 17 of the stud 15, whereupon the contents will run down through the opening in the head 20 and through the holes 14 into the hand underneath. A spring 23 may be secured to the top 4 to force the container 18 down if it should stick.

The knob 16 is formed with a shoulder next to the stem 15 so that when the container 18 is lifted, this knob will pull any of the contents next to it through the hole in the head 20. The jarring caused by the up and down movement of the container 18, keeps the contents loose. This is of importance as

soap-powders are liable to cake and arch, which would prevent free discharge. When freely running powders are in the container 18, the stud 15 and plug 17 may be omitted, 5 as the opening in the head 20 will be closed by the bottom 13.

The construction of a dispenser for tooth-powder will be similar to that shown and described, but the size will be less. Talcum 10 and other toilet powders may be similarly stored for use.

I claim.

1. In a dispenser, a receptacle having a discharge opening in its bottom and also 15 having an opening in its upper end, a container mounted therein having a discharge opening in its bottom, said receptacle including a closure arranged to normally close the last mentioned discharge opening, manually 20 operable means for elevating the container to a position in which the closure no longer closes the discharge opening in the container whereupon the contents of the latter are discharged through the opening in the bottom 25 of the receptacle, the container being freely removable through the upper end of the receptacle without interference with the closure.
2. In a dispenser, the combination of a cylindrical receptacle having a bottom, a stud projecting upward from the center of the bottom and having a pointed end and an enlarged portion next to the bottom, a container within the receptacle and having an orifice in its lower head normally closed by 35 the enlarged portion of the stud, said bottom of the receptacle having an opening adjacent said stud, and manually operable means for raising said container to withdraw the stud from the orifice and permit 40 the escape of the contents of the container through the orifice and the opening in the bottom of the receptacle.

3. As a new article of manufacture, a container for powdered substances comprising 45 a cylindrical body and end closures, one of said end closures sloping outwardly to a discharge opening, an easily perforated membrane closing said opening, a dispensing 50 receptacle adapted to secure said container and dispense its contents and having means extending into said discharge opening to close the same, and manually actuated means for simultaneously establishing a free passage through the opening and causing the 55 discharge of the contents.

4. In a dispenser, the combination of a receptacle having a bottom, a stud projecting upward from the bottom and having an enlarged end and an enlarged portion next to the bottom, a container within the receptacle and having an orifice in its lower head normally closed by the enlarged portion of the stud that is next to the bottom, said bottom 65 of the receptacle having an opening adjacent

said stud, and manually operable means for moving the container in respect to the stud to withdraw the stud from the orifice and permit the escape of the contents of the container through the orifice and the opening in 70 the bottom of the receptacle.

5. A dispensing apparatus comprising a receptacle having an opening in its lower portion, a stud carried by and projecting into the receptacle, a support in the receptacle and a package thereon, said package being arranged to be pierced by said stud, 75 said support and said receptacle constituting members, and manually operable means for imparting movement to one of the members 80 in respect to the other to withdraw the stud from the package and allow the contents of the latter to be discharged through the hole therein and through the opening in the receptacle.

6. A dispensing apparatus comprising a receptacle having an opening in its lower portion, a tapering stud carried by and projecting into the receptacle, a support in the receptacle and a package thereon, said package being removable from said receptacle and arranged to be pierced by said stud, said support and said receptacle constituting members, and manually operable means for imparting movement to one of the members 95 in respect to the other to withdraw the stud from the package and allow the contents of the latter to be discharged through the hole therein and through the opening in the receptacle.

7. A dispensing apparatus comprising a receptacle having an opening in its upper end and also having an opening in its lower end, a member carried by and projecting into the receptacle, a support in the receptacle, said member being arranged to project above a portion of the support, said support and said receptacle constituting two members, manually operable means for imparting movement to one of the members in respect to the other, a container for a commodity to be dispensed, the receptacle being arranged to freely receive and to allow the withdrawal of the container through its upper end, whereby, when the container is inserted into the receptacle in position to rest upon the support, it is perforated by the projecting member, and whereby, when the manually operable means is afterward actuated, the projecting member is withdrawn 115 from the container to allow the contents of the latter to be discharged by gravity 120 through the opening in the lower end of the receptacle.

8. A dispensing apparatus comprising a 125 fixed receptacle having a hole in its lower portion, a stud carried by and projecting into the receptacle, a support in and movable in respect to the receptacle, a finger-piece secured to the support and projecting exte- 130

riorly of the receptacle, and a package within the receptacle in position to be pierced by said stud, whereby, when the finger-piece is seized, the support and container may be moved in the receptacle to allow the contents to pass through the opening made by the stud and to be discharged through the hole in the lower portion of the receptacle.

9. In a dispenser, the combination of a cylindrical receptacle having a bottom, a stud projecting upward from the center of the bottom, a container within the receptacle and having an orifice in its lower head normally closed by the stud, said bottom of the

receptacle having an opening adjacent said stud, and manually operable means for raising said container to withdraw the stud from the orifice and permit the escape of the contents of the container through the orifice and the opening in the bottom of the receptacle.

In testimony whereof I have signed this specification in the presence of two subscribing witnesses.

FRANCIS C. OSBORN.
